WRAY FALWELL, OF ALLSTON, MASSACHUSETTS

VALVE SPRING LOCK TOOL

Application filed January 28, 1932. Serial No. 589,369.

My present invention relates to valve spring lock tools, and more particularly to tools for use in holding in place the valve spring locking member, sometimes called a key, which holds the valve spring in place under tension in automobile engines and other engines of similar type in which poppet valves are used for gas intake and exhaust purposes.

In nearly all locking devices of this nature there is also provided in combination with the key member, a saddle member which receives the bottom coil of the spring and at the same time prevents the key member from being displaced when the valve spring is in operating position.

Whenever it is necessary to grind the valves of an engine of the class above mentioned, the valve spring must be lifted with a valve spring lifting tool and the key removed before the grinding work can be done.

In some types of locking members, such as the one illustrated in the accompanying drawing, the key lock member will fall out easily when the valve spring is lifted, but the real difficulty comes in replacing this lock member when the valve is reassembled due to the small working space present and the fact that the locking key must be held in place until the saddle member is seated around it.

In my present invention I have designed a tool which will hold the locking member in place around the valve stem until the saddle member is in place. In fact, the saddle member pushes the tool out of the way at the same time it seats around the locking key.

The locking key member for which this tool is designed is made in two pieces the sides of which are tapered from top to bottom in a conical manner.

The principal object of my invention is an improved valve spring lock tool;

Another object is a valve spring lock tool which holds the locking member in place

around the valve stem until the spring saddle member has seated around the locking member;

Still another object is a valve spring lock tool which is automatically displaced by the saddle member when the saddle member has become engaged around the lock member, and

Other objects and novel features comprising the construction and operation of my invention will appear as the description of the same progresses.

Referring to the drawing illustrating my invention;

Fig. 1 is a vertical cross-section of a valve spring assembly showing the spring compressed and the locking member in place being held by the jaws of the tool;

Fig. 2 is a cross-section taken on the line 2-2 of Fig. 1 showing the tool with the locking member in place about the valve stem;

Fig. 3 is an inner side elevation of one of the split halves of a locking member;

Fig. 4 is an inner side elevation of one of the jaw portions of the tool;

Fig. 5 is a plan view of one of the tool jaw spring and locking member holders;

Fig. 6 is a side elevation of the spring member shown in Fig. 5, particularly showing the normal curved formation of the said spring member, and

Fig. 7 is a side elevation of a modified form of spring.

Referring more in detail to the drawing, 80 10 indicates a valve stem around which is placed a compression spring 11. The upper end of the compression spring 11, in a typical automobile engine, bears against an overhanging portion of the cylinder block, not 85 shown in Fig. 1. The bottom of the valve spring 11 is held by a saddle member 12 through which the valve stem 10 passes.

In Fig. 1, I have shown the saddle and valve spring compressed upward as is the case 90

when the valve unit is being assembled. The saddle and valve spring being held up by means of a valve lifting tool, a portion of the upper jaw of which is indicated at 13. In 5 this position the lower end of the valve stem 10 is exposed, as shown in Fig. 1 so that the split cone locking members 14 may be placed around the annular groove 15 provided on the valve stem 10 for the purpose.

- 10 By an examination of Fig. 1 it will be noted that the saddle member 12 is provided with an upwardly depressed chamber 16, the sides of which are of conical formation similar to the sides of the locking members 14 such that 15 when the saddle member 12 is allowed to drop over the locking members 14, the members 14 cannot become dislodged from the valve stem groove 15.

My present invention is principally concerned in a tool to hold the locking members 14 in the valve stem groove 15 while the saddle member 12 is lowered over such locking members. The tool comprises a pair of oppositely opposed jaw members 17, the handle 20 portions 18 of which are offset from the jaw portions and crossed in the conventional manner of a pair of pliers, a rivet 19 being provided at the cross over portion on which to pivot the jaws 17.

- 30 The jaws 17 are recessed on the inner sides adjacent the working end of the tool as indicated at 20 and adapted to conform to the conical sides of the locking members 14 with particular reference to its lowermost portion.

On the extreme end of the jaw portions 17 and adjacent their inner sides I have provided an extension portion 21 better shown in Fig. 4.

- 40 On the lower sides of the jaw members 17 I have placed a flat spring member 22 which is also recessed at 23 similar to the jaw portions 17 of the tool except that the recess 23 is of a lesser diameter or radius than 45 the recess 20. At 24 I have provided an opening through which rivets 25 may be placed for the purpose of securing the member 22 to the jaw 17 and upon which the member 22 may pivot. The front portion of the member 22 is provided with a cap portion 26 within 50 which the extension portion 21 of the jaws 17 may slide when the member 22 is pivoted about the rivet 25. Also on the inner side of the member 22 I have provided vertical 55 stop members 27.

It will be noted that the normal condition of the member 22 is curved, as shown in Fig. 6, the material being composed of spring steel such that when the extension end 21 60 of the jaw members 17 are inserted under the cap 26 and the rivets 25 in place the lower surface of the jaws 17 and the upper surface of the members 22 are held together by friction unless acted upon by considerable 65 outside force.

When it is desired to load the tool the members 22 are pushed toward each other and a half section of the locking member 14 is placed on the member 22, the curved side of the locking member being placed adjacent the recessed side 20 of the jaw 17 after which the members 22 are pivoted outward on the rivets 25, the result of which is to clamp the two half portions of the member 14 in the jaws 17. The members 14 may now be placed around the valve stem as shown in Fig. 1 and the saddle allowed to drop into place, the chamber 16 catching the member 14 and holding it against the valve stem just prior to displacing the jaws 17.

Fig. 7 illustrates a modified form of the spring member 22 as indicated by 22a. The only difference in the member 22 and 22a is that the member 22 is provided with a top cover portion on the cap portion 26 while member 22a has no such cover portion, and the spring curvature of the member 22a is reversed from the member 22. When the member 22a is used in place of the member 22 it is unnecessary to reduce the end 21 of the member 17 as shown in Fig. 4 but such extension member may continue outward to the same limit as shown in Fig. 4 but maintained at the same thickness as the rest of the jaw member 17. In operation either 22 or 22a will produce the same result both being held in contact against the sides of the jaws 17 by means of friction.

Having thus described my invention what I claim as new, is:

1. A tool for holding in place valve stem spring locking members comprising a pair of flat bladed pliers, the inner front surfaces adapted to receive split cone lock members, spring members adapted to engage the bottom portions of said lock members, friction means adapted to the jaws of said pliers and said lock members, substantially as shown and described.

2. A tool comprising a pair of pliers adapted to hold split cone valve spring locking members comprising a pair of recessed jaw members adapted to receive a portion of the sides of said split cones, spring members pivoted to the bottom of said jaw members adapted to hold a portion of the bottom of said split cones, means for clamping said split cones in said recessed jaw members comprising flanges located on the inner sides of said spring members, means for maintaining friction between said spring members and said jaw members, said friction means comprising cap portions located on the end of said spring members adapted to engage over the ends of said jaws.

3. In a valve spring locking tool, a pair of pliers having recessed conical inner surfaces adapted to receive the conical sides of a split cone valve spring locking member, pivoted spring members located below said recessed

conical surfaces adapted to support the bottom of said split cone locking members, substantially as shown and described.

4. A tool for holding split cone valve
5 spring keys comprising in combination, a
pair of conically recessed plier members, slid-
able flat spring members pivoted to the under
side of said recessed members, means for
holding said cone members in said recesses.
10. In testimony whereof I have affixed my
signature.

WRAY FALWELL.
